Fraenkel & Richards,
ATTORNEYS

UNITED STATES PATENT OFFICE.

DAVID ZAIDEN, OF EAST ORANGE, NEW JERSEY.

MECHANICAL DOLL.

1,382,708.

Specification of Letters Patent. Patented June 28, 1921.

Application filed December 14, 1920. Serial No. 430,676.

To all whom it may concern:

Be it known that I, DAVID ZAIDEN, a citizen of Russia, residing at East Orange, in the county of Essex and State of New Jersey, have invented certain new and useful improvements in Mechanical Dolls; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 The present invention relates, generally, to improvements in dolls; and the invention has reference, more particularly, to a novel construction of mechanically operated doll adapted to perform movements in simulation of the so called "shimmy" dance.

20 The invention has for its principal object to provide a construction of doll provided with a novel arrangement for mounting the arms in connection therewith in combination with a novel mechanical motor device for producing a rhythmic movement of the arms and shoulders of the doll in simulation of the so called "shimmy" dance.

25 Other objects of the present invention, not at this time more particularly enumerated, will be clearly understood from the following detailed description of the same.

30 With the objects of the present invention in view, the same consists, primarily, in the novel construction of mechanical doll adapted to produce the movements above mentioned as hereinafter set forth; and, furthermore, the invention consists in the novel arrangements and combinations of the various 35 devices and parts, as well as in the details of the construction thereof, all of which will be hereinafter more fully described and claimed.

35 The invention is clearly illustrated in the accompanying drawings, in which:—

40 Figure 1 is a back view of the novel mechanical doll, made according to and embodying the principles of the present invention.

45 Fig. 2 is a side view of the motor mechanism thereof detached from the doll, and drawn on an enlarged scale.

50 Fig. 3 is a vertical transverse section, taken on line 3—3 in said Fig. 2; Fig. 4 is a 55 detail horizontal section through the same, taken on line 4—4 in said Fig. 2; and Fig. 5

is a detail vertical section, taken on line 5—5 in said Fig. 2.

Similar characters of reference are employed in all of the hereinabove described views, to indicate corresponding parts.

Referring now to said drawings, the reference character 1 indicates the body of a doll, preferably made of molded material in any suitable design, and provided in its trunk portion 2 with a hollow interior or chamber 3 having openings 4 leading therefrom at its opposite sides adjacent to the shoulder portions 5. The rear wall of said trunk portion 2, which constitutes the back 65 of the doll, is provided with a centrally longitudinally disposed opening 6.

Adapted to be placed within the chamber 3, by passing the same through the opening 6, and then being secured in place by supporting brackets 7, which are attached thereto, is the frame 8 of a motor mechanism. Said brackets 7 are provided at their opposite ends with outwardly off-set perforated lugs or ears 9, which are engaged against 75 the marginal portions of the trunk 2 which bound the opening 6, and then secured by passing fastening devices, such as the screws 10, therethrough and into the trunk portion, thus serving to securely support the motor 80 mechanism within the chamber 3 of said trunk portion.

Said motor mechanism comprises a spindle 11 journaled in the lower portion of said frame 8, said spindle having an outwardly 90 projecting portion 12, which extends outwardly through the opening 6, and upon which is secured a winding key 13. The reference character 14 indicates a spirally wound motor spring, the inner end of which 95 is secured to said spindle 11, while the outer end 15 of which is anchored upon or fixed to the lower cross bar 16 of said frame 8. Fixed on said spindle 11 by its hub 17 is a driving clutch 18 provided with spring 100 clutch dogs or fingers 19. Loosely mounted on said hub portion 17 of said driving clutch 18 is a driving gear 20 provided on its inner face with clutch dog receiving pockets or steps 21. When the motor spring 14 is 105 wound up the rotation of the spindle is reversed whereby said clutch dogs or fingers 19 ride over the pockets or steps 21 of the gear 20. When the spindle is rotated by the stored energy of the motor spring 14, 110 in the normal operative direction, each clutch dog or finger 19 is engaged in a

pocket or step 21, and so maintained in such engagement as to cause the gear 20 to be rotated with the spindle 11 and driving clutch 18. Journaled in said frame 8 above 5 said spindle 11 is another spindle 22 upon which is fixed a pinion 23 which meshes with and is driven by said gear 20. Said spindle 22 also carries an intermediate gear 24. Journaled in said frame 8 above said 10 spindle 22 is a third spindle 25 which carries a pinion 26 adapted to mesh with and be driven by said intermediate gear 24. Said spindle 25 also carries a toothed escapement wheel 27. Journaled in said frame 8 above 15 said spindle 25 is an arbor 28 upon which is fixed an escapement dog or anchor 29, the latter having an impulse pallet 30 at one end, and a locking pallet 31 at the other end, which alternately coöperate with said 20 toothed escapement wheel 27. Connected with said arbor 28, so as to be oscillated transversely by the escapement mechanism, is an upwardly projecting lever 32. Mounted on the free end of said lever 32 is a transverse bar 33, the opposite free ends of which 25 project respectively through the openings 4 of the trunk-portion 2 of the doll. Fixed to the outer ends of said bar 33 are the arms 34 of the doll. Connected with said frame 30 8 are a pair of parallel check or momentum stop springs 35 and 36, which straddle said lever 32, so that as the latter oscillates it will alternately be engaged by said springs, whereby its impulsive movement in each 35 direction will be checked and reversed in synchronism with the operation of the escapement mechanism.

The operation of the doll, constructed as above described, is as follows:

40 The motor spring 14 is wound up by turning the winding key 13 to rotate the spindle 11 in the reverse direction, thus storing the energy of the motor spring. When the winding key is released the motor spring 45 begins to unwind thereby causing a rotation of the spindle 11 in an operative direction. The rotation of the spindle 11 is transmitted through the driving clutch 18 to the driving gear 20. The driving gear imparts, through 50 the intermediate train of pinions and gear, 23, 24 and 26, a rotative movement to the escapement wheel 27. The rotation of the escapement wheel 27 acts upon the escapement dog or anchor 29 to cause an oscillation of the same, whereby the arbor 28 is 55 rocked to in turn oscillate the lever 32. The lever 32, as it oscillates transversely, rocks the bar 33 whereby the respective ends of the same are caused to swing up and down, 60 thus in turn causing the arms 34 to partake of the rhythmic movement thus produced so that the upper ends or shoulder portions 34' of said arms rise and fall rhythmically, thus simulating to a very 65 realistic degree the movements of the so

called "shimmy" dance. When the doll is clothed the illusion is enhanced, since the movement of the arms and shoulder portions is imparted to the dress, thereby causing a swaying movement of the latter which adds 70 considerably to the effect and life-likeness of the simulated dance.

It will be apparent that the mechanism is very simple, and is of such a character that the dolls can be produced cheaply and with 75 little labor.

I am aware that some changes may be made in the arrangements and combinations of the various devices and parts, as well as in the details of the construction of the same, 80 without departing from the scope of my present invention as set forth in the foregoing specification, and as defined in the appended claims. Hence, I do not limit my invention to the exact arrangements and 85 combinations of the various devices and parts as described in said specification, nor do I confine myself to the exact details of the construction of said parts as illustrated in the accompanying drawings. 90

I claim:

1. In a doll of the kind described, a body having a chambered interior and provided at opposite sides adjacent to the shoulder portions thereof with openings, a transverse 95 bar within said body having its respective ends projecting through said side openings, arm portions carried by the ends of said bar, a pivoted transversely oscillatable lever upon the free end of which said bar is supported, and a spring motor mechanism within 100 said body for actuating the oscillatable movement of said lever and said bar carried by the latter.

2. In a doll of the kind described, a body 105 having a chambered interior and provided at opposite sides adjacent to the shoulder portions thereof with openings, a spring motor mechanism frame, brackets for attaching said frame to said body and supported 110 within the interior of the latter, an escapement mechanism mounted in said frame having an arbor adapted to be rocked by the operation of said escapement mechanism, a spring motor mechanism mounted in said 115 frame, transmission gearing intermediate said spring motor mechanism and escapement mechanism, a lever carried and oscillated by said arbor, a transverse bar fixed to the free ends of said lever, the respective 120 free ends of said bar projecting through said side openings of said body, and arm portions carried by the free ends of said bar.

3. In a doll of the kind described, a body 125 having a chambered interior and provided at opposite sides adjacent to the shoulder portions thereof with openings, a spring motor mechanism frame, brackets for attaching said frame to said body and sup- 130

- ported within the interior of the latter, an escapement mechanism mounted in said frame having an arbor adapted to be rocked by the operation of said escapement 5 mechanism, a spring motor mechanism mounted in said frame, transmission gearing intermediate said spring motor mechanism and escapement mechanism, a lever carried and oscillated by said arbor, a transverse bar 10 fixed to the free end of said lever, the respective free ends of said bar projecting through said side openings of said body, arm portions carried by the free ends of said bar, and a pair of momentum stop springs 15 supported by said frame to straddle said lever so as to be alternately engaged by said lever when the same is oscillated.
4. In a doll of the kind described, a body having a chambered interior and provided 20 at opposite sides adjacent to the shoulder portions thereof with openings, a rotatable toothed escapement wheel mounted within said body, means for actuating said escapement wheel, an arbor carrying an escapement wheel anchor coöperating with said escapement wheel, a lever carried and oscillated by said arbor, a transverse bar fixed to the free end of said lever, the respective free ends of said bar projecting through said 25 side openings of said body, and arm portions carried by the free ends of said bar.
5. In a doll of the kind described, a body having a chambered interior and provided 30 at opposite sides adjacent to the shoulder portions thereof with openings, a rotatable toothed escapement wheel mounted within said body, means for actuating said escapement wheel, an arbor carrying an escapement wheel anchor coöperating with said escapement wheel, a lever carried and oscillated by said arbor, a transverse bar fixed to the free end of said lever, the respective free ends of said bar projecting through said side openings of said body, and arm portions carried by the free ends of said bar.
6. In a doll of the kind described, a body having a chambered interior and provided 35 at opposite sides adjacent to the shoulder portions thereof with openings, a rotatable toothed escapement wheel mounted within said body, means for actuating said escapement wheel, an arbor carrying an escapement wheel anchor coöperating with said escapement wheel, a lever carried and oscillated by said arbor, a transverse bar fixed to the free end of said lever, the respective free ends of said bar projecting through said side openings of said body, and arm portions carried by the free ends of said bar, and a pair of fixed momentum stop springs 40 adapted to straddle said lever so as to be alternately engaged by said lever when the same is oscillated.
7. In a doll of the kind described, a body having a chambered interior and provided 45 at opposite sides adjacent to the shoulder portions thereof with openings, a rotatable toothed escapement wheel mounted within said body, means for actuating said escapement wheel, an arbor carrying an escapement wheel anchor coöperating with said escapement wheel, a lever carried and oscillated by said arbor, a transverse bar fixed to the free end of said lever, the respective free ends of said bar projecting through said side openings of said body, and arm portions carried by the free ends of said bar, and a pair of fixed momentum stop springs 50 adapted to straddle said lever so as to be alternately engaged by said lever when the same is oscillated.
8. In a doll of the kind described, a body having a chambered interior and provided 55 at opposite sides adjacent to the shoulder portions thereof with openings, a rotatable toothed escapement wheel mounted within said body, means for actuating said escapement wheel, an arbor carrying an escapement wheel anchor coöperating with said escapement wheel, a lever carried and oscillated by said arbor, a transverse bar fixed to the free end of said lever, the respective free ends of said bar projecting through said side openings of said body, and arm portions carried by the free ends of said bar, and a pair of fixed momentum stop springs 60 adapted to straddle said lever so as to be alternately engaged by said lever when the same is oscillated.
- In testimony that I claim the invention set forth above I have hereunto set my hand this 9th day of December, 1920.
- DAVID ZAIDEN.
